(57) **CLAIM**

The ornamental design for an orthotic insert for shoes, as shown and described.

DESCRIPTION

FIG. 1 is a bottom perspective view of embodiment one, of an orthotic insert for shoes, showing our new design.

FIG. 2 is a top plan view thereof.

FIG. 3 is a lateral side elevational view thereof.

FIG. 4 is a bottom plan view thereof.

FIG. 5 is a partially enlarged cross-sectional view, taken along the line 5-5 of FIG. 4.

FIG. 6 is a medial side elevational view thereof.

FIG. 7 is a rear elevational view thereof.

FIG. 8 is a front elevational view thereof.

FIG. 9 is a bottom perspective view of embodiment two, of an orthotic insert for shoes, showing our new design.

FIG. 10 is a top plan view thereof.

FIG. 11 is a lateral side elevational view thereof.

FIG. 12 is a bottom plan view thereof.

FIG. 13 is a partially enlarged cross-sectional view, taken along the line 13-13 of FIG. 12.

FIG. 14 is a medial side elevational view thereof.

FIG. 15 is a rear elevational view thereof; and,

FIG. 16 is a front elevational view thereof.

Shading lines shown in the drawings are intended to represent the approximate three-dimensional contour of the design, and are not intended to indicate surface decoration. The broken lines in the figures show unclaimed subject matter only and form no part of the claimed design.
